Primary Examiner — Lauren Calve

(74) Attorney, Agent, or Firm — Ballard Spahr LLP

(57) **CLAIM**

We claim the ornamental design for a hanger system, as shown and described.

DESCRIPTION

FIG. 1 is an isometric view of a hanger system according to our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an isometric view of a hanger system according to a second embodiment;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

1 Claim, 10 Drawing Sheets
